HAND PUMP

Robert W. Hyde, Cincinnati, Ohio, assignor to Superior
Tool and Grinding Co., House Springs, Mo., a corpo-
ration of Missouri

Filed July 13, 1961, Ser. No. 65,909

Term of patent 14 years

(Cl. D65—1)

FIGURE 1 is a front elevational view of a hand pump embodying my new design.

FIGURE 2 is a rear elevational view of the pump.

FIGURE 3 is a top plan view of the pump.

FIGURE 4 is a bottom view of the pump.

FIGURE 5 is an end view of the pump.

FIGURE 6 is a cross sectional view through the handle of the pump taken on the line 6—6 of FIGURE 4.

I claim:

The ornamental design for a hand pump, substantially as shown.
